UNITED STATES PATENT OFFICE.

EDWARD KIRBY BOTTLE, OF ELMIRA, NEW YORK, ASSIGNEE TO AMERICAN SALES BOOK COMPANY, LIMITED, OF TORONTO, ONTARIO, CANADA, A CORPORATION OF ONTARIO, CANADA.

MANIFOLDING SALES-BOOK.

1,295,105.

Specification of Letters Patent. Patented Feb. 25, 1919.

Application filed December 22, 1916. Serial No. 138,298.

To all whom it may concern:

Be it known that I, EDWARD KIRBY BOTTLE, a citizen of the United States, residing at Elmira, in the county of Chemung and State of New York, have invented certain new and useful Improvements in Manifolding Sales-Books, of which the following is a full, clear, and exact description, such as will enable others skilled in the art to which it appertains to make and use the same.

This invention relates to manifolding salesbooks.

An object of this invention is to provide a salesbook in which multiple copies may be made from a single record in a practical manner, and more particularly in which five or less copies may be made at the will of the manipulator, in a more efficient manner.

Another object of this invention is to enable one or more of the records to be retained in the book without interference with the subsequent use of the book, in a more satisfactory manner.

Other objects will be in part obvious and in part pointed out hereinafter.

The invention accordingly consists in the features of construction, combination of elements and arrangement of parts which will be exemplified in the construction herein-after set forth, and the scope of the application of which will be indicated in the following claims.

One embodiment of my invention is illustrated in the accompanying drawings, forming part of this specification, and wherein similar reference characters refer to similar parts throughout the several views, in which—

Figure 1 is a perspective view of one embodiment of this invention.

Fig. 2 is a similar view showing the book in operative position;

Fig. 3 is a view showing the manipulation of the book;

Fig. 4 is a perspective view of a modified form showing the pads in superposed relation, with a portion of one pad broken away to show the carbon sheet; and

Fig. 5 is a perspective view of the modified form, showing the sheets arranged in manifolding position.

In the embodiment of the invention illustrated in Figs. 1, 2 and 3, there are provided two pads so disposed as to permit the leaves

of the one pad to be placed upon and between the leaves of the other pad, with transfer sheets having four carbon faces which may be placed between the sheets of the pads to form a quintuplicate record. These pads may be held in associated operative relation by means of a support 1. One of these pads, as 2, is hingedly attached, as at 3, to one edge of this support, and the other of the pads, as 4, may be attached to another edge of the support, which is conveniently the edge opposite the hinge 3. As the second pad need not be hingedly connected to the support, it is convenient to bind it fast, as, for example, by staples 5. The pad 2 is conveniently made of a set of superimposed sheets bound together along one edge 6, as by staples 7, each sheet being folded upon itself to form two leaves, as a free leaf 8 and a bound leaf 9, joined along one edge, as 10, which, in the form illustrated, is opposite to the binding edge 5. The binding edge 6 of the pad 2 may conveniently be the edge opposite to hinge 3. The pad 4 may consist of separate leaves, as 11, 12 and 13, held together by the fastening means 5. By this construction, it will conveniently be possible to interpose the leaves of the pad 4 either under or on top of the pad 2, or between the leaves of the top or uppermost set of the pad. Suitable transfer material is so arranged as to be operatively associated with said pads, and is conveniently bound into and on top of the pad 2. This transfer material is double faced, having a plurality of carbon faces to permit a multiple record to be made, and is conveniently made in the form of a sheet folded upon itself, like the sheets of the pad 2 to provide two leaves, an under or bound leaf 14 and an upper or free leaf 15, and bound in the pad 2. To enable the unbound leaf of the top set from the pad 2 to be readily grasped and removed from beneath the carbon without first removing the carbon, a notch 16 is made in both leaves of the carbon in position to expose a corner of the free end of the free leaf.

In Figs. 4 and 5 is illustrated a modification of this invention which may be employed when the used leaves of the pad 4 are detached from the pad as soon as used. In this form the pads 2 and 4 may be conveniently attached together at one end, as by a common binding means, for example,

the staples 19. This modification provides a simpler and cheaper book where the retention of the copies in the book is not required.

The bound sheets of the pad 2 and the sheets of the pad 4 will preferably be provided with weakened portions, as a line of perforations, shown at 17 and 18, respectively, and the sheet constituting the leaves 8 and 9 will preferably be perforated at the fold 10 so that the copies may be readily removed from the book, if desired, and so that the leaves 8 and 9 may be readily separated.

With this construction, by removing the free leaf of the top set from beneath the transfer material, so that the transfer material will lie between the two leaves of the top set of the pad 2, the sheets of the pad 4 may be inserted between and upon the two leaves of the transfer sheet.

20 The manipulation of this book is as follows: With the book in the position shown in Fig. 1 and the pad 4 superposed on the pad 2 in the position in which they would normally rest, the unused leaves of the pad 4 are thrown back to expose the pad 2. The original leaf, as 8, of the top set from the pad 2, may now be removed from beneath the carbon sheet, so as to permit the lower leaf 14 of the carbon sheet to rest in contact with the leaf 9, hereinafter called the duplicate leaf, of the top sheet from the pad 2. The top leaf, as 15, of the transfer sheet may now be turned back to expose the upper face of the lower carbon leaf 14.

35 When it is desired to make a quintuplicate record, two sheets 11 and 12 from the pad 4 are then laid over the carbon leaf 14, to constitute, respectively, the quintuplicate and quadruplicate copies, and the top leaf 15 of the carbon sheet is superposed thereon. Another sheet from the pad 4, as 13, is laid over the carbon leaf 15 to form the triplicate copy, and the original sheet 8 is folded over on top thereof.

40 It will be obvious that if desired, the top leaf 8 of the top sheet from the pad 2 may be placed beneath the sheet 13 from the pad 4, with which it lies in contact. Thus such sheet 13 would become the original and the sheet 8 the triplicate. It is preferable, however, to use the book as described because, since it is desirable to make the triplicate transparent because its record is reversed and on the under surface, and the duplicate 45 is preferably opaque since its record is direct on the front surface, it is more economical to provide transparent sheets in the pad 4 than to make one-half of the sheet of the pad 2 transparent.

50 With the construction outlined, it is obvious that any writing upon the original sheet 8 will be copied reversed upon the under side of the triplicate and quintuplicate sheets and will be copied directly upon 55 the top side of the quadruplicate and dupli-

cate sheets. By reason of the fact that the triplicate and quintuplicate sheets have their records reversed upon the reverse side of the sheet, these sheets will preferably be made of transparent material.

70 Where less than five copies may be needed, a less number of sheets from the pad 2 may be used. Thus by using only two sheets from this pad a quadruplicate record may be obtained or by using only one, a triplicate. Where only a triplicate record is required, the sheet from the pad 2 may be placed in any one of the three positions which the sheets of the pad 2 occupy in making a quintuplicate record, and where 80 a quadruplicate record is required, any two of these three positions may be used.

85 Where it is desired to enable five copies to be made, the transfer sheet will be surfaced on both sides of both sheets; but one or more of these surfacings may be omitted if a less number of copies is sufficient.

90 The original and duplicate sheets may now be torn from the book and from each other along the weakened lines 17 and 10, and as many as desired of the triplicate, quadruplicate and quintuplicate sheets may be torn from the book along the weakened line 18. The pad 2 may now be folded upwardly around the hinge 3, and those copies 95 which it is desired to have remain in the book may be folded down therebeneath between the pad 2 and the support and the pad 2 folded thereon. The book is now ready for a repetition of the manipulation described.

100 By the construction recited, it will be obvious that as many of the records as desired may be allowed to remain in the book without interfering with subsequent manipulation of the book.

105 By the foregoing construction are accomplished, among others, the objects hereinbefore set forth, as well as others which will be obvious.

110 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

115 It is also to be understood that the language used in the following claims is intended to cover all of the generic and specific features of the invention herein described and all statements of the scope of the invention, which, as a matter of language, might be 120 said to fall therebetween.

125 Having described my invention, what I claim as new and desire to secure by Letters Patent is:

1. A device of the character described 130

- comprising, in combination, a set of superimposed folded sheets, a set of leaves associated with said sheets so as to be interposable between the folds of the uppermost sheet of the first mentioned set and a folded transfer sheet providing double face transfer leaves arranged to be interposed between the folds of said uppermost sheet, and to receive, between its folds, leaves of said second mentioned set. 5
2. A device of the character described comprising, in combination, a set of superimposed folded sheets, a set of transparent leaves associated with said sheets so as to be interposable between the folds of the uppermost sheet of the first mentioned set, and a folded transfer sheet providing double face transfer leaves arranged to be interposed between the folds of said uppermost sheet, and to receive, between its folds, leaves of said second mentioned set. 10
3. A device of the character described comprising, in combination, two sets of sheets so arranged that the leaves of one may be interposed between those of the other, and a folded transfer sheet providing double face transfer leaves between said sets and adapted to be interleaved with the leaves of each set. 15
4. A device of the character described comprising, in combination, a support, a pad comprising leaves joined together and to said support along one edge of said leaves and said support, a second pad hingedly connected to the opposite edge of said support comprising leaves joined together along the edge opposite the said hinged edge of said pad and each folded back upon itself to form two sheets joined together along the edge adjacent to said hinge, whereby the sheets of said first-mentioned pad may be 20
- placed between and upon the sheets of the second-mentioned pad, and transfer material comprising a sheet bound integrally with said second-mentioned pad and folded upon itself to form two leaves, each coated upon both sides, adapted to be inserted between and upon the leaves of said pad to enable a quintuplicate record to be made, said transfer sheet being notched to permit 25 the upper leaf of the top set of the second pad to be readily removed from beneath the carbon sheet. 45
5. A device of the character described comprising, in combination, a set of superimposed folded sheets, a set of leaves associated with said sheets so as to be interposable between the folds of the uppermost sheet of the first mentioned set and a folded transfer sheet providing double face transfer leaves 30 arranged to be interposed between the folds of said uppermost sheet, and to receive, between its folds, leaves of said second mentioned set, each of said transfer leaves being notched to expose an edge of one of said other leaves. 50
6. A device of the character described comprising, in combination, two sets of sheets so arranged that the leaves of one may be interposed between those of the other, and a folded transfer sheet providing double face transfer leaves between said sets and adapted to be interleaved with the leaves of each set, each of said transfer leaves being notched to expose a portion of one of said other leaves. 55

In testimony whereof I affix my signature, in the presence of two witnesses.

EDWARD KIRBY BOTTLE.
